UNITED STATES PATENT OFFICE.

JACOB KRAUSS, OF LEXINGTON, KENTUCKY.

RUNNING-GEAR FOR VEHICLES.

SPECIFICATION forming part of Letters Patent No. 748,080, dated December 29, 1903.

Application filed January 21, 1903. Serial No. 140,006. (No model.)

To all whom it may concern:

Be it known that I, JACOB KRAUSS, a resident of Lexington, in the county of Fayette and State of Kentucky, have invented certain new and useful Improvements in Running-Gear for Vehicles; and I do hereby declare the following to be a full, clear, and exact description of the invention, such as will enable others skilled in the art to which it appertains to make and use the same.

My invention relates to an improvement in running-gear for vehicles, and more particularly to the front-truck construction, the object of the invention being to provide an improved construction of this character which will enable the vehicle to turn in a comparatively short space and dispense with the necessity for offsets or cut-unders in the vehicle-body.

With this object in view the invention consists in certain novel features of construction and combinations and arrangements of parts, as will be more fully hereinafter described, and pointed out in the claims.

In the accompanying drawings, Figure 1 is a plan view illustrating my improvements. Fig. 2 is a side view, and Fig. 3 is a rear view; and Fig. 4 is a view in vertical section, taken through the center of Fig. 3, the bolt 10 and 30 the nut thereon being shown in elevation.

1 represents the wheel-axle, on which elliptical springs 2 are secured, and these springs are connected at their top by a cross-bar 3, rigidly secured thereto.

To the upper face of the springs 2 is rigidly secured by clips or otherwise a bar 4. This bar 4 is bent into the general shape shown—that is, its ends 6 6 are bent and project at an approximate right angle to the main or intermediate portion thereof and are secured between their ends to the springs, as above explained, and they are also bent upward and constructed to receive the thills. The main portion of this bar 4 is thus disposed some 45 distance back or in rear of bar 3 and in a vertical plane in rear of axle 1, and this main or intermediate portion of bar 4 is made up of an upper metal plate 12, a lower metal plate 13, and an intermediate filler of wood 14^a, secured together and to the side members of the bar by bolts 14, as clearly shown in Fig. 3. While I preferably thus construct the bar for

the purposes of economy and elasticity, it may be made of one continuous bar of metal, and when this bar is hereinafter referred to and mentioned in the claims it is to be understood that it may be a continuous bar of metal or comprise several sections secured together. The upper plate 12 has a tubular lug 7 to enter a socketed plate 15, secured to the body 6 17, and receive the king-bolt 10. A strap 16 extends rearward from the king-bolt to the vehicle-body and serves to relieve this connection of twisting strain due to the draft on the vehicle.

A half-wheel 8 is secured on bars 3 and 4 and forms the lower member of the fifth-wheel. The upper member of the fifth-wheel comprises a complete circle or ring 9, secured to the body timbers or sills, and the king-bolt 7 10 enters tubular lug 7 and pivotally connects the body and gear.

To the bar 4 the steps 11 are rigidly secured, and the several parts referred to may be secured together in any approved manner.

By constructing my improvements as above explained it will be seen that while the weight of the vehicle-body is equally distributed and supported from the center of the springs the pivotal point of the gear 8 80 is in a vertical plane somewhat in rear of the axle, thus permitting the wheels to be moved a considerable distance in turning without striking the body, and thus enable the vehicle to make a much shorter turn than 85 would be the case were the pivotal point in the same vertical plane as the axle. I provide a close-coupled vehicle, dispensing altogether with the necessity for a coupling-pole for drawing the rear part of the gear. I also 90 equally distribute the weight throughout the fifth-wheel and support from the center of the springs and can hitch the horse close to the vehicle. I can also provide large front wheels and at the same time have a short 95 turning-gear without the necessity for a cut-under in the body, thus giving this additional room to the vehicle.

Changes might be made in the general form and arrangement of the parts described without departing from my invention, and hence I do not confine myself to the precise details set forth, but consider myself at liberty to make such slight changes and alterations as

fairly fall within the spirit and scope of my invention.

Having fully described my invention, what I claim as new, and desire to secure by Letters 5 Patent, is—

1. In a vehicle-gear, the combination with an axle and two full elliptical springs secured at their centers to the axle, of a cross-bar located directly over the axle and connecting the upper members of said springs at the center of each spring, a U-shaped bar having its parallel arms disposed upon the springs and secured thereto at the ends of the cross-bar connecting the centers of the 15 springs, the cross member of said U-shaped bar disposed parallel to and a distance rearwardly of the cross-bar connecting the springs and a fifth-wheel member secured centrally upon the cross member of the U-shaped bar 20 and also secured to the cross-bar connecting the springs.
2. In a vehicle-gear, the combination with an axle and full elliptical springs secured at their centers thereto, of a cross-bar located 25 immediately over the axle and connecting the upper members of said springs at the center of each spring, a U-shaped bar having two parallel members disposed upon the springs and secured thereto at the ends of the cross- 30 bar connecting the centers of the springs, the cross member of said U-shaped bar disposed a distance in rear of said cross-bar, a fifth-wheel member secured to the cross member

of the U-shaped bar and steps fixed to the parallel arms of said U-shaped bar.

3. In a vehicle-gear, the combination with an axle and full elliptical springs secured at their centers thereto, of a U-shaped bar having its parallel arms located upon said springs and secured thereto and its cross member located in rear of the axle, a fifth-wheel member secured to said bar, a king-bolt passing through the cross member of the U-shaped bar, and a rod secured at one end to said king-bolt, extending rearwardly and adapted 40 at its rear end for attachment to a sill of the vehicle.

4. In a vehicle-gear, the combination with an axle and two full elliptical springs secured centrally thereto, of a bar over the axle and secured at its ends to the top centers of the elliptical springs, and a U-shaped bar having side members disposed at right angles to the axle and secured to the top centers of the springs, the forward ends of said side 50 members of the U-shaped bar constructed to receive a draft device and the cross member of said U-shaped bar disposed rearwardly of the axle and parallel therewith.

In testimony whereof I have signed this 60 specification in the presence of two subscribing witnesses.

JACOB KRAUSS.
